UNITED STATES PATENT OFFICE.

FREDERIC W. HILD, OF LOS ANGELES, CALIFORNIA.

UNIVERSAL ROTARY EQUIPMENT FOR EARTH DRILLING.

Application filed March 3, 1923. Serial No. 622,582.

To all whom it may concern:

Be it known that I, FREDERIC W. HILD, a citizen of the United States, residing at Los Angeles, in the county of Los Angeles and State of California, have invented a new and useful Universal Rotary Equipment for Earth Drilling, of which the following is a specification.

This invention relates to the rotary method of earth boring. In this system, the string of drilling tools is made up of a suitable bit screwed into the bottom of the drill rod which consists of rods or pipes screwed together; the upper end of the drill rod is screwed into a square or fluted drill stem; this stem is screwed into a swivel. The whole string is vertically hinged to a mast or derrick by means of a suitable block and tackle which engages the swivel.

This string of tools is rotated by what is commonly designated the rotary machine which is placed on suitable supports on the ground or the derrick floor directly over the hole. The square or fluted drill stem passes through a like shaped opening in the rotary machine. The rotary machines hitherto in common use, is a circular rotating table member driven by a pinion which in turn is driven by suitable belt, chain, or gear drive.

A plurality of bushings which are usually split or hinged are employed to impart rotation to the drill stem and also to support the drill rod or pipe when it is necessary to add or remove rods or pipe. Thus the center of the rotary table receives first a master bushing. The master bushing is usually of square or fluted formation at the upper end thereof and of conical formation at the lower end thereof and the master bushing, which is split into two sections, has the same exterior formation as the interior of opening in the rotating table member. The master bushing is prepared to receive a drive bushing through which the rotation of the table member is transferred to the drill stem. The opening in the master bushing which receives the drive bushing is also squared or fluted at the upper end thereof and of conical formation at the lower portion thereof. If the drill stem employed be square or fluted in cross section, a corresponding hole is provided in the drive bushing through which the drill stem may slide longitudinally as the drilling progresses, but

which positively rotates the drill stem, the drill rod, and the cutting tool as the table is rotated.

During the driving of the drill stem, the stresses placed upon the rotating table are comparatively small, but when pipe is being raised or lowered within the well, tapered slips or wedges are provided between the pipe and the master bushing for gripping and holding the string of pipe in any desired position, thus placing considerable weight and expansive force upon the master bushing and the rotary members. This expansive force E is,

$$E = \frac{W}{2 \tan A} \quad 70$$

where

W =the weight of the string of tools or pipe.

A =the angle of the taper of the wedges or slips.

The angle A is necessarily small, sometimes about 9° , and when a long string is thus supported, the expansive force is about 3.16 times the weight of the string. That is, a string weighing about 100,000 pounds imparts not only the stress due to its weight, but also about 316,000 pounds expansive or bursting force to the master bushing and the rotary table. It follows then that all the rotating members must of necessity be heavy and massive in the hitherto rotary equipment. In most rotary machines, ball or roller bearings are used. The heavy weights placed on the rotating table and bushing must be carried by these.

In the making up or breaking out of a string of pipe, the rotary machine is at times employed for screwing up or unscrewing the joints. In order to accomplish this with the ordinary type of table, the top stand of pipe which is being unscrewed from the drill pipe string is held stationary while the string of pipe held by slips in the master bushing is rotated by revolving the rotary table, thus causing the unscrewing of the joint between the stand of pipe to be removed and the string of pipe. This practice of rotating a heavy string of pipe, by the rotary table causes excessive stresses to be placed in the roller or ball bearings and the races by which the rotary table is supported upon the base cast-

ing. Since the areas of contact between the rollers and the races is exceedingly small, the unit stresses are correspondingly very high, and even though very accurately and uniformly machined, the rollers are apt to chip and break and the races to be abraded. The disruption of the surfaces soon results in unsatisfactory rotating conditions and vibration in the equipment.

10 In other hitherto rotary machines having special provision for using the rotating members to make up or break out pipe or drill rods, the operator must first prepare the machine for holding the pipe stationary by shifting levers and by other additional manual operations. Nevertheless the workman can at his option disregard the special provisions and may rotate the pipe while it is being carried by the rotating members.

15 In the hitherto types of rotary machine, the master bushing partially fills the opening through which pipe or casing may be passed and supported by the machine. Thus 20 $12\frac{1}{2}$ inch pipe is the largest size which can be handled by a rotary machine that will pass a 20 inch bit so when larger pipe must be set, the machine must be pulled aside and the pipe set by other means; or 25 else, a much larger and more massive machine must be used.

20 But greater diameter and greater mass cause greater inertia and greater momentum, which are very serious factors in the 30 machinery for earth boring. Manifestly, the greater the momentum or fly wheel effect of the rotary machine, the greater the liability of distorting and twisting off the long slender drill; and, the more the inertia, the greater are the stresses and the liability 40 to breakage of the chains, gearing and driving mechanism. Furthermore, the fly wheel effect due to the large diameter and heavy massive construction of the rotating members, restricts the permissible speed of rotation of the drill and correspondingly restricts the rate of drilling the hole.

35 One object of my invention is to provide a rotary drilling equipment in which the 45 rotating members are always free of the heavy weights and expansive forces now imposed by the strings of drill rods or pipe.

45 Another object of the invention is to provide a drilling equipment employing a single rotary table which may be utilized to 55 make up and break out a string of pipe or drill rods without the possibility of rotating the machine supported string of pipe or drill rod.

60 Another object of the invention is to achieve the minimum mass and diameter of the rotary table and drive bushing, consistent with proper mechanical strength and with the physical dimensions of the bits

and pipe to be handled, and thereby reduce 65 the momentum and inertia of the rotating members to the attainable minimum.

When handling a string of casing that is passed through, but not supported by, the hitherto rotary machines, it has been customary to place a spider or step ring on a suitable foundation or subbase underneath the rotary machine. This necessitates workmen under the derrick to perform the essential operations of manipulating the pipe supporting means. Such proceeding, unsatisfactory and risky at best, is prohibitive in the frequent work of making up or breaking out drill pipe, on account of the serious risk of personal injury to the workmen, the uncertain resultant work and the excessive cost. Likewise it is equally dangerous and impractical to do such work from above on the derrick floor, if the pipe supporting means are below the rotary table. Experience has shown that these means must be at or near the upper surface of the rotary table for reliable and efficient results.

65 One of the important objects of this invention is to dispose the pipe supporting member in the best working position, and as later described, this member may project above the surface of the rotary table.

70 In the hitherto rotary machines, the lubrication of most of the rotating members is applied directly to the parts by hand. This is usually uncertain and irregular and is generally either excessive or insufficient. It is an object of this invention to provide 75 automatic and properly controlled lubrication for all the bearings of the machine.

75 In the hitherto rotary machines, numerous manual operations are necessary when removing the drive bushing and the master bushing because of hand operated locks. 80 latches levers and clamps.

80 A further object of this invention is to eliminate these manual operations, clamps and locks and to simplify the latching of the drive bushing by causing the latch for 85 this to operate automatically to open and close when inserting or removing the bar or hook used to lift the drive bushing out of or into the rotary table.

85 In the hitherto rotary machines when using bits larger than the circular opening through the machine, the workmen must go under the derrick floor and screw the bit to the drill pipe from beneath the machine. There is risk of dropping the bit in the 90 hole, and this risk also obtains when smaller bits are screwed to the pipe by the rotary table.

90 In addition to the other objects, this invention enables the passage of much larger fishtail or flat bits through the machine so 95 that in fact the largest practical size now in use can be passed through even though the

machine herein described is much smaller in diameter than any of the hitherto rotary machines having like pipe size capacity. Furthermore means are provided by this invention for holding the bits so they cannot fall into the hole while being attached or removed from the drill pipe.

Other objects of my invention will become evident from the detailed description herein taken in conjunction with the drawings.

My invention provides a rotary machine which consists of a rotary table mounted upon a base frame and driven in the customary manner. The machine also includes a hold down bracket, a single drive bushing which may be solid or split or hinged, one or more slip rings, slip ring elevators, slips, a hook for lifting the drive bushing into or out of the rotary table and a bit bracket for holding bits when attaching or removing the latter to the drill pipe.

The rotary table is employed solely for rotating purposes, such as the rotating of the drill stem, or for rotating the upper stand of a string of pipe or drill rods for the purpose of making up or breaking out the string.

Owing to the fact that no heavy loads due to the drill rods or pipe are sustained, the rotating members are made of weight and mass sufficient only for the comparatively light duty of rotating the drill stem. As no master bushing is employed, the rotary table has a relatively larger opening for the passage of the pipe. Accordingly its diameter and mass and therefore its inertia are relatively less than the hitherto rotary machines.

In this opening and situated entirely within the rotary table, but not touching it, is the pipe supporting member which is a simple slip ring having a tapered hole for receiving slips or wedges for gripping the pipe against both downward displacement and rotation. The slip ring rests on the upper surface of the base frame and projects upward to or above the surface of the rotary table. It is held in position against rotation and upward displacement either by an ordinary bolt engaging the base or as in the preferred form herein described, by a lug which engages the base.

By the use of the arrangement above described, it is possible to support a string of drill pipe or casing within the hole without any of the weight nor the resultant expansive force thereof being placed upon the rotary table or its bearings. Furthermore, the string of drill pipe or casing thus supported in the hole cannot be rotated; but lengths of pipe can be screwed onto or from the upper end of the supported string by means of suitable tongs driven by the table and rotating said table in the direction to cause the screwing up or unscrewing of the joint.

The manipulation of the slips and the work of handling the pipe can all be done safely and efficiently on the derrick floor and in the most favorable working position.

The drive bushing is novel and a distinct improvement. Its sole function is to transmit the rotation of the table to the drill stem during the drilling operations, which as before stated is comparatively light duty. It is not required to transmit heavy weights nor expansive forces to the rotary table, because the square or fluted drill stem moves freely in longitudinal direction through the center of the drive bushing. Thus the latter is relatively much lighter than other bushing and rotating gripping devices and it therefore contributes substantially to the reduction of weight and inertia of the rotating members of this invention. This drive bushing engages the rotary table directly, positively and tightly. The circular, conical, tapered surface of the lower outer portion causes the bushing to fit tightly into the corresponding surface in the table. If the bushing is split or hinged, this forces the halves closely and tightly together, and furthermore accurately and rigidly centers the drill stem opening.

Plural bushings and other gripping devices as provided in the hitherto machines do not permit this certainty of tight fit and accurate centering and the consequent looseness augments the impact and shocks which stress the machine during drilling.

The hollow annular space between the outer and central portions of the herein described drive bushing, permits the latter to surround a large part of the slip ring without contact. This arrangement of the slip ring and the drive bushing thus projecting into each other results in compactness and economy of material and space, so that the top of the rotary table is brought closer to the machine base and the derrick floor than in the hitherto machines. Thereby this invention realizes another of its objects because the requirement of the table close to the floor is highly important to facilitate the work in the various machine operations.

The base has important novel features. The circular opening for passing the pipe is further enlarged by two slots diametrically opposite each other. As the bit must always be larger in diameter than the casing so as to insure clearance for the latter, these slots permit the passage of flat bits suitable for the largest casing that can be passed through the machine. Therefore, all the operations of affixing and detaching the maximum size bit is done above the derrick floor.

Other advantages of the invention and further objects thereof will be made evident hereinafter.

Referring to the drawings which are for illustrative purposes only:

this view the latch element thereof is shown in retracted position.

Fig. 19 is a view of the drive bushing lock shown in Fig. 18, and is taken as indicated by the arrow B in Fig. 18.

Fig. 20 is a view showing an alternative means for removing the stationary socket.

As shown diagrammatically in Fig. 1, it is customary in the rotary system of drilling to mount a rotary machine 11 upon the floor 12 of a derrick 14. Through the rotary table 15 of the rotary outfit 11, and supported from a swivel head 16 which is suspended by tackle 19, there extends a drill stem 20 which is generally of square cross section. This drill stem is attached by means of a tool joint 21 to a string of drill pipe 22 having a bit 23 attached at the lower end thereof for the purpose of penetrating the subterranean formations. My invention concerns chiefly the rotary 11 and equipment associated therewith.

As shown in Figs. 2 and 3 of the drawing I provide a cast base frame 25 which supports at the forward end thereof a rotary table 26 having bevel gear teeth 27 formed upon its underside which are engaged by a bevel pinion 28 supported upon a drive shaft 29 sustained in suitable bearings 30. The shaft 29 may be rotated by any convenient means such as chain or gears. As a matter of simplicity, I show a standard form of sprocket 32 which is keyed to the shaft 29 and may be driven from the draw works by a chain in the customary manner.

The rotary table 26 has a large opening 33 therein which is of polygonal formation at the upper end thereof, as indicated at 34 in Fig. 2, and merges as indicated at 35 with a conical formation at the lower end thereof. The base frame 25 has a circular opening 37 formed therein concentric with, and of but slightly smaller diameter than, the opening 33 in the rotary table 26. In a suitably formed annular channel 38 surrounding the opening 37 there is placed a lower ball race 39 upon which conical rollers 40 roll. The rotary table 26 provides an inner circular wall 42 which extends downwardly from the conical portion 35 of the opening 33 across the inner faces of the rollers 40 to the base, indicated at 43 in Fig. 4, just below the edge of the lower race 39. In an annular recess 44 formed between the inner wall 42 and an outer wall 45 an upper race 46 is placed.

The rotary table 26 is secured down by an improved form of hold-down ring 48 provided with oil receptacles 49 from whence ample lubrication is delivered through oil passages 50 to the frictional engaging surfaces of the member 48, and the rotary member 26. The opening 37 provided in the base 25 is enclosed by a circular ring or lip 52 having diametral notches 53 formed therein as shown in Fig. 6. As

shown in Fig. 3 a forged or cast socket 55 is supported upon the ring 52 and has a short cylindrical extension 56 which is chamfered off at the lower edge thereof, as indicated at 57, and extends downwardly into the opening 37, thus being held centralized with the rotary table 26. The interior face 59 presented by the socket 55 is of inverted cone shape, as shown, and may be made of such size that the lower end of the conical opening 60 will accommodate the largest size of drill pipe employed. The socket 55 has two projections 62 diametrically disposed around the extension 56, which projections extend into the notches 53 and prevent rotation of the socket 55. A pin 63 may be employed as indicated in Fig. 3 for the purpose of holding the socket 55 against being lifted.

Several different sockets are employed in the practice of the invention, and constitute a set in which each socket has a different utility. The socket 55 shown in Fig. 3 provides a stationary non-rotatable support for drill pipe, and small diameter casing when it is being made up and lowered into the well. For casing of intermediate diameter, a socket such as shown at 55, but having a larger conical opening therethrough may be employed. When handling a large diameter casing, a socket such as indicated at 65 in Fig. 4 is employed. This socket has its smallest diameter 66 substantially equal to the diameter of the opening 37 of the ring 52 and expands in conical form as the upper end thereof is approached, as shown at 67. Downwardly projecting lugs 68 are provided which extend into the notch 53 to prevent rotation of the socket and holes 70 are provided into which the bolt 63 may extend to hold the member 66 against being raised.

For the purpose of driving the drill stem 71 shown in Fig. 3 a drive bushing 72, which may be divided into halves 73 and 74 as shown in Fig. 2, is employed. The drive bushing has the upper portion 75 thereof of the same polygonal outline as the upper portion 34 of the opening 33 in the rotary table 26 while the lower flange portion of the bushing 72 is in the form of a cone 77 which fits the conical portion 35 of the opening 33. Through a centrally disposed hub 78 there extends a squared hole 79, through which the drill stem 71 is slidable, and by which the drill stem is engaged in such a manner that it will be readily rotated by the table 26.

As shown in Fig. 5 of the drawing, my invention readily adaptes itself to the making up of a string of casing or drill pipe. In this figure I show a string of drill pipe 80 having a box end 81 of a tool joint at the upper end thereof. This string of drill pipe 80 is supported against dropping and also

against rotation by slips 82 and 83 which operate between the interior conical face 59 of the socket 55, and the exterior face of the drill pipe 80, with a wedging action which securely sustains the string of drill pipe. As shown in the sectional view, Fig. 11, one slip 83 may be employed for the purpose of preventing the rotation of the drill pipe 80 and a pair of the slips 82 may be employed to grip the pipe against downward movement. It will be perceived that the slips 82 have horizontal teeth 84 formed therein, while slip 83 is provided with vertical teeth 85. The weight of the drill pipe 80 causes the slips 82 and 83 to be firmly wedged between the pipe and the socket 55, thus causing the imbedment of the teeth 84 and 85 of the slips in the face of the drill pipe. The weight of a length of drill pipe supported in the manner just described is received entirely by the socket 55 and is transferred through the frame 25 to the derrick sills; the expansion stresses of the slips, however, are received by and confined to the socket 55.

Above the box end 81 of the tool joint shown in Fig. 5, is illustrated the pin end 87 of a tool joint situated on the lower end of a stand of drill pipe 88, this stand 88 is being attached to the upper end of drill stem by screwing together the ends 81 and 87 constituting the tool joint. As before mentioned the string of drill pipe 80 is held stationary in the sockets 55. Therefore, the screwing up of the joint is accomplished by rotating the stand 88. This is done by means of pipe tongs 90 having a short lever or handle extension 91 whereby it may be supported by a member 92 which is held upon a pin 93 placed in one of the pin holes 94 provided in the table 26, as shown in Fig. 6. The upper end of the pin 93 extends into a hole formed in the member 92, and a screw 95 which is screwed into the pin 93 and operates in a slot 96 formed in the attachment 92 prevents the member 92 from being lifted off the pin. With the clamp 90 placed in engagement with the stand 88 as shown in Fig. 5, it is possible by rotating the table to cause the tool joint to be screwed up. Casing may be made up in the same manner, and by reversing the rotation of the table joints in drill pipe and casing may be broken.

It will be perceived that the member 92 is slidable upon the pin 93 and that as a joint is made or broken and the stand 88 is raised or lowered, the member 92 either raises or lowers upon the pin 93 so that no strains are placed upon the rotary table 26 or the pin 93.

In the standard type of rotary table it is, as before-mentioned, customary to brake out pipe by holding the stand 88 stationary and rotating the string of drill pipe 80 there-

underneath by rotating the table in which the string of drill pipe is supported by slips. This manner of breaking joints is a matter of natural consequence with the standard 5 form of rotary equipment owing to the fact that drill pipe or small sized casing being lowered in the well is supported, through the use of slips, by the rotary table. The weight of a string of pipe often approaches 10 and at times exceed 100,000 pounds. It will be recognized that such stresses upon the rotary table are excessive and that the rotation of the table when supporting such a weight is very detrimental to the roller bearings 15 upon which the table is supported, causing their rapid deterioration as previously mentioned herein.

From the preceding description of my invention, it will be plainly evident that the 20 placing of excessive weight, such as the weight of a string of drill pipe or casing, on the rotating elements of the rotary machine is entirely impossible; and therefore misuse of the rotary equipment in this respect is 25 likewise impossible as no provision is made for supporting pipe from the table 26. During the making up of a drill pipe or casing string, the weight of such string is supported by the socket 55, and during the rotation 30 of the drilling string the weight thereof is supported from the swivel head 16.

When it is desired to set a casing which is of larger diameter than the socket 55 will accommodate, this socket may be removed, as shewn in Fig. 6, and a larger size socket such as shown at 65 seated upon the ring 52. This removal of the socket 55 is accomplished by the use of a slip ring elevator 100 which is comprised of a 35 pair of cooperating members 101 which are of conical outline as indicated at 102 and are of an interior diameter to fit closely around the drill pipe indicated at 103. These members are dropped down into the 40 socket 55 and the loops 105 thereof are placed over hook formations 106 which are constructed by forming U shaped channels 107 in the upper edge of the socket member 55 as shown in Figs. 6 and 7. When 45 the socket 55 is thus engaged by the loops, the drill pipe 103 is lifted, causing the collar or tool joint 109 upon the lower end thereof to engage the lower extremity 110 of the elevator 100, thereupon transferring 50 through the loops 105 the lifting action of the string of drill pipe, with the result that the socket 55 is raised through the rotary table 26, as shown in Fig. 6, and may be kept upon the drill pipe until its further use is required; whereupon the drill 55 pipe is lowered through the rotary and the socket 55 deposited upon the ring 52. It will be noticed that the upper edge of the ring 52 is chamfered off as indicated at 60 65 112. This is done for the purpose of pro-

viding a guide or flare which assists in centralizing the socket 55 as it is lowered in the bore 37 of the ring 52.

My invention also provides an attachment for use in screwing the drill pipe upon 70 the bit which is to be employed for drilling, thus making it possible to make up the entire drilling string with my device and thereby eliminating manual screwing up of any joints therein. As shown in Figs. 75 8 and 9, for the purpose of holding a drill bit 115 while the drill pipe 116 is being connected thereto, I employ a jack 118 which provides a horizontal slot 119 into which the blade 120 of the bit 115 is 80 dropped, as shown in the view. When held in this manner by the jack 118, the drill bit is sustained against rotation while the 85 drill pipe string 116 is screwed therein by the employment of tongs 90 in the manner shown in Fig. 5. This jack 118 may be very simply formed from a pair of angles 122 placed with their downwardly extending legs 123 facing, as shown at Fig. 12, and connecting the ends thereof together by 90 means of U straps 125 which are bent to the correct width to be received in the notches 53 in the ring 52, thus supporting the jack so that it will not rotate. Laterally extending angle arms 126 may be employed, if desired, for obstructing and bridging the 95 opening on each side of the jack and also furnishing an additional stabilizing support therefor.

The improved form of hold-down ring 100 48 which my invention employs completely encircles the lower portion of the table 26 as shown in Fig. 9. This ring 48 is preferably made of segments 130 which are provided with outstanding flanges 131 and 105 131a as shown in Figs. 16 and 17 so that the segments of the hold-down ring may be bolted together as shown at 132 and may also be bolted down upon the plates 133 provided upon the forward corners of the 110 base frame 25. These base plates 133 are raised portions on the frame disposed in four positions around the lower ball race and are provided with holes 134 into which studs 135 as shown in Fig. 14 are placed 115 which pass through holes 136, indicated in Fig. 17, in the horizontally extending flanges at the lower edges of the segments 130 for the purpose of securing the hold-down ring upon the shims 137 situated upon the plates 133. The frame 25 is secured on the derrick floor by anchor bolts 139, shown in Fig. 13, which extends through holes 140. The hold-down ring segments 130 provide a continuous substantially vertical circular web 142 which extends entirely around the lower portion of the rotary table, except at that point where it extends between the channel 45 in the rotary member and the drive pinion 28. At this 120 125 130

point which is indicated at 144 in Fig. 3, the web 142 is interrupted and the inwardly projecting ring 144 which is formed at the upper edge of the web 42 extends alone 5 between the drive pinion 28 and the rotary table 26. The openings 50 are drilled into the oil receptacles 49 from an annular groove 145 formed in the inner face of the ring 144. This groove is provided with a felt 10 oil distributing strip 146 which by absorption regulates the flow of oil through the openings 50. The oil receptacles 49 are preferably formed integrally with the flanges 131 and are situated above the 15 bolts 132.

Positive means of lubrication are provided as shown in Figs. 13, 14 and 15 in the form of oil receptacles 148 comprised of vertical walls 149 which are cast integral- 20 ly with the base 25 and located in positions adjacent to the rearward hold-down ring mounting plates 133, and in alignment with the drive pinion 28 so that the drive pinion housing 151 may be bolted on the top 25 of the receptacles 148 by cap screws 152 which thread into openings 153. The housing 151 does not extend entirely across the receptacles 148 but has doors or covers 155 hinged thereto as shown in Fig. 1 which 30 covers may be raised to permit the pouring of oil through removable screens 156 into the oil receptacles.

As shown clearly in Figs. 13 and 15, a hole 160 is drilled down from the bottom 35 161 of the receptacle 148 and a sloping hole 163 is drilled from the annular recess 164 in which the lower ball race 39 is placed and communicates with the hole 160 which is preferably of sufficient depth as shown in 40 Fig. 15 to provide a sediment trap which may have a hole 167 drilled thereinto from the side of the casting 25 as indicated in dotted lines in Fig. 13 for use as a clean out which may be ordinarily closed by a cap or plug 45 168. Grooves cut in the face of the ball race 39 and the face of the recess 164 co-operate in forming an annular channel 170 through which oil from the receptacles 148 may circulate. Radial holes 171 are drilled 50 at intervals through the vertical wall of the race 39 through which oil from the channel 170 is distributed through the rollers 40. The flow of oil from the receptacles 148 is regulated by the valve shown in Fig. 15. 55 This valve consists of a plug 172 which is threaded into the opening 160 and has a threaded central opening 173 therein, into which a screw 174 extends. This screw is relieved on a slope as indicated at 175 so that by changing the length to which the screw enters the plug 172, the oil passage 60 may be regulated. A spring 176 is provided for retaining the screw 174 in set position and engages a notch formed in the

head of the screw so that the rotation of the 65 screw is thereby prevented.

In the hitherto rotary machines, the lubrication is not regular nor controlled; the bearings at times being flooded with an excess of lubricant and immediately thereafter 70 allowed to run dry. My invention provides a positive, simple, and even distribution of lubricant.

In the present type of rotary machines, various means are employed for holding the 75 drive bushing in seated position, certain of these means consisting of plates or collars which are bolted to the table and which extend over portions of the drive bushings. Such devices require manual attention and 80 thus constitute a source of additional labor and a consumption of time.

My invention, however, provides a means for securely locking the drive bushing in place which is entirely automatic in its operation, being in locking engagement when the drive bushing is in place and being simultaneously unlocked with the placing of the elevator hooks in the openings provided in the drive bushing therefor. Each of the 85 halves of the drive bushing 72 has a pair of openings 180 formed therein to which elevator hooks 181 shown in Fig. 18 are extended for the purpose of engaging the underside of the web 182 of the bushing with 90 the toe or hook portion 183 of the elevator hook in such a manner that the drive bushing may be conveniently lifted from the opening provided in the table 26. The latch means as indicated at 185 in Figs. 2 100 and 18 consist of bolts 186 which are situated in recesses 187 formed in the outer face of each portion of the drive bushing and extend rearwardly through openings 188 and have laterally extending pins 189 formed 105 upon the inner end thereof. The inner end of the bolt 186 is also flattened as indicated in Fig. 19 and extends through a vertical slot 190 in a lever 191 which pivots at 192 to the inner face of the conical portion 110 of the drive bushing. The pins 189 rest against the outer faces 193 of the side portions 194 which define the slot 190. The upper end 195 of the lever 191 is bent inwardly as shown in Fig. 18 so that this inner end 195 will cover the opening 180 when 115 the lever is in the position indicated by the dotted lines 196 in Fig. 19, and in full lines in Fig. 18. The spring 197 acts against the head 198 and serves to hold the bolts normally in the position indicated by the dotted lines 199. When the elevator hooks 181 are inserted in the openings 180, the lever 191 is pushed inwardly into the position shown 120 in full lines in Fig. 18 whereupon the engagement thereof with the pins 189 causes the retracting of the bolt 186 as shown in full lines in the figure so that throughout 125

the time that the hooks 181 are in lifting position the latch means 185 is disposed in non-engaging position. The drive bushing may then be lifted freely from the rotary table 26 and when again inserted and the elevator hooks 181 removed, the latch means 185 will immediately become operative. This automatic operation of the latch means eliminates the labor now expended in manually operating the various devices now employed for holding down the drive bushings.

As shown in Fig. 20 I find it very convenient, instead of employing the elevator 100 to remove the socket 55, to provide outwardly extending lugs 200 upon the lower end of the drill shank or the lowest section of the line of drill tubing 201. It will be seen from this view that upon removing the bit 202 from the well, the lugs 200 will engage the lower face of the socket 55 and thereby remove it also.

I claim as my invention:

1. In a rotary machine of the class described, the combination of: a supporting frame having an opening therethrough; a rotary member supported above said opening for service as a drive member, said rotary member having an opening therein through which a string may be passed; removable engagement means associated with said rotary member whereby said string may be suitably rotated; a socket non-rotably mounted in said opening in said supporting frame; and an elevator cooperative with said string for lifting said socket from said frame.

2. In a rotary machine of the class described, the combination of: a supporting frame having an opening therethrough; a rotary member supported above said opening for service as a drive member, said rotary member having an opening therein through which a string may be passed; removable engagement means associated with said rotary member whereby said string may be suitably rotated; a socket non-rotably mounted in said opening in said supporting frame; an elevator cooperative with said string for lifting said socket from said frame; and slips, receivable in said socket, for gripping said string.

3. In a rotary machine of the class described, the combination of: a supporting frame having an opening therethrough; a rotary member supported above said opening for service as a drive member, said rotary member having an opening therein through which a string may be passed; removable engagement means associated with said rotary member whereby said string may be suitably rotated; a socket non-rotably mounted in said opening in said supporting frame; an elevator cooperative with said string for lifting said socket from said

frame; and slips, receivable in said socket, 65 for gripping said string against downward movement and rotation.

4. In a rotary machine of the class described, the combination of: a supporting frame having an opening therethrough; a rotary member supported above said opening for service as a drive member, said rotary member having an opening therein through which a string may be passed; removable engagement means associated with 70 said rotary member whereby said string may be suitably rotated; a socket, having a conical bore, non-rotably mounted in said opening in said supporting frame; and an elevator cooperative with said string for lifting said socket from said frame, said elevator consisting of cooperating conical segments adapted to fit within said socket and around said string so as to be lifted by said string, and suspension engagement means 80 operative between the upper ends of said segments and the upper portion of said socket for lifting said socket.

5. In a rotary machine of the class described, the combination of: a supporting frame having an opening therethrough; a rotary member supported above said opening for service as a drive member, said rotary member having an opening therein through which a string may be passed; removable engagement means associated with 95 said rotary member whereby said string may be suitably rotated; a socket, having a conical bore, non-rotably mounted in said opening in said supporting frame; and an elevator co-operative with said string for lifting said socket from said frame, said elevator consisting of cooperating conical segments adapted to fit within said socket and around said string so as to be lifted by 100 projections on said string, and suspension engagement means operative between the upper ends of said segments and the upper portion of said socket for lifting said socket.

6. In a rotary machine of the class described, the combination of: a supporting socket member adapted to grip a string of pipe, which extends therethrough, with the cooperation of suitable slips; a frame for supporting said socket; and an elevator cooperative with said string for lifting said socket from said frame, said elevator consisting of cooperating conical segments adapted to fit within said socket and around said string so as to be lifted by said string, and engagement means operative between 115 said segments and said socket for lifting said socket.

7. In a rotary machine of the class described, the combination of: a supporting socket member adapted to grip a string of pipe, which extends therethrough, with the

cooperation of suitable slips; a frame for supporting said socket; and an elevator cooperative with said string for lifting said socket from said frame, said elevator consisting of cooperating conical segments adapted to fit within said socket and around said string so as to be lifted by projections on said string, and engagement means operative between said segments and said 10 socket for lifting said socket.

8. In a rotary machine of the class described, the combination of: a supporting socket member adapted to grip a string of pipe, which extends therethrough, with the cooperation of suitable slips; a frame for supporting said socket; and an elevator cooperative with said string for lifting said socket from said frame, said elevator consisting of cooperating conical segments adapted 20 to fit within said socket and around said string so as to be lifted by said string, and suspension engagement means operative between the upper ends of said segments and the upper portion of said socket for lifting said socket.

9. In a rotary machine of the class described, the combination of: a supporting socket member adapted to grip a string of pipe which extends therethrough; with the cooperation of suitable slips; a frame for supporting said socket; and an elevator cooperative with said string for lifting said socket from said frame, said elevator consisting of cooperating conical segments adapted 30 to fit within said socket and around said string so as to be lifted by projections on said string, and suspension engagement means operative between the upper ends of said segments and the upper portion of said 40 socket for lifting said socket.

10. In a rotary machine of the class described, the combination of: a supporting base frame having an opening therein; a rotary member upon said frame; means for driving said rotary member; a bearing between said frame and said rotary member; oil receptacles upon said frame from which oil is distributed through ducts to said bearing; and means for regulating the flow of oil 50 from said receptacles to said bearing.

11. In a rotary machine of the class described, the combination of: a supporting base frame having an opening therein; a rotary member upon said frame; means for driving said rotary member, said means including a drive pinion; a bearing between said frame and said rotary member; and oil receptacle on said frame upon each side of said drive pinion, from which receptacles oil is distributed through ducts to said bearing; and adjustable means for regulating the flow of oil from said receptacles to said bearing, a pinion housing member secured upon and extending between said oil receptacles, the ends of said housing partially cov-

ering said receptacles; and covers hinged to said ends of said housing member, for covering the remaining portion of said receptacles.

12. In a rotary machine of the class described, the combination of: a member having a bushing receiving opening therein; a bushing for said opening; locking bars supported in said bushing in such a manner that the ends thereof may extend outwardly into 70 openings formed in the inner face of said member; springs for holding said locking bars outwardly; and means associated with said locking bars for withdrawing them from engagement with said openings, said 75 means being actuated by the insertion of lifting means in suitable receptive openings in said bushing.

13. In a rotary machine of the class described, the combination of: a member having a bushing receiving opening therein; a bushing for said opening; locking bars supported in said bushing in such a manner that the ends thereof may extend outwardly into 80 openings formed in the inner face of said member; springs for holding said locking bars outwardly; and means associated with said locking bars for withdrawing them from engagement with said openings, said 85 means being actuated by the insertion of lifting means in suitable receptive openings in said bushing, said means consisting of levers disposed with the upper ends thereof obscuring said receptive openings when said locking bars are in extended position. 90

14. In a rotary machine of the class described, the combination of: a supporting frame having an opening therein through which a drill bit may pass; a rotary table supported above said frame opening; and having also an opening through which said bit may pass; and means supported in said opening in said frame for holding said bit against dropping and rotation while the drill pipe to which said tool is attachable is 100 screwed thereto by said rotary table. 105

15. In a rotary machine of the class described, the combination of: a supporting frame having an opening therein through which a tool may pass; a rotary table supported above said frame opening, and having also an opening through which said tool may pass; and means supported in said opening in said frame for holding said tool against dropping and rotation while the 110 drill pipe to which said tool is attached is screwed thereto by said rotary table. 115

16. In a rotary machine of the class described, the combination of: a supporting frame having an opening therein through which a tool may pass; a rotary table supported above said frame opening, and having also an opening through which said tool may pass; and means supported by said frame, in a position concentric with said 125 frame, 130

- opening therein, for holding said tool against dropping and rotation while the drill pipe to which said tool is attached is screwed thereto by said rotary table.
5. 17. In a rotary machine of the class described, the combination of: a supporting frame; a rotary table supported upon said frame, said table having a radially extending annular projection; and a continuous segmental hold-down ring extending entirely around said table and engaging said annular projection thereupon in a manner to prevent upward relative movement of said table, the segments of said hold-down ring being provided with outwardly extending flanges whereby the segments may be bolted together in continuous circular arrangement, flanges for bolting said hold-down ring to said frame, and oil receptacles formed integrally with and between said outwardly extending flanges and a circular wall of said hold-down ring segments which communicates with the bearing face of said hold-down ring through suitable oil channels.
10. 18. In an elevator co-operative with a rod having projections, for lifting a loose collar; surrounding said rod, a plurality of bushing segments inserted between the collar and the rod; and engagement means between the collar and the segments.
15. 19. An elevator for lifting a loose socket surrounding a string of pipe, said elevator consisting of a plurality of bushing segments, adapted to fit between the pipe and the socket, the interior bore of said bushing segments being less than the exterior diameter of the pipe couplings; and, suitable links for engaging said bushing segments with the socket.
20. 20. In a rotary machine of the class described, the combination of: a rotary table having a groove in its outer periphery; a base frame supporting said rotary table; a removable retaining ring secured to the base frame and fitting into the groove in said rotary table; said retaining ring having a smaller groove for receiving a wick of wool or corresponding material for oil absorbing and distributing purpose.
25. 21. In rotary drilling equipment, the combination of: a rotary table; means supporting said rotary table; a removable string supporting member concentrically disposed within said rotary table; and a string having projections formed on the lower end thereof whereby said removable member is lifted from operative position and retained upon the lower end of said string in readiness for replacement when said string is again lowered through said rotary table.
30. 22. In rotary drilling equipment, the combination of: a rotary table; means supporting said rotary table; a removable string supporting member concentrically disposed within said rotary table, said string supporting member consisting of a continuous ring; and a string having projections formed on the lower end thereof whereby said removable member is lifted from operative position and retained upon the lower end of said string in readiness for replacement when said string is again lowered through said rotary table.
35. 23. In rotary well drilling equipment, the combination of: a support; a rotary table turnably mounted on said support, said table having a centralized bushing receiving opening therein of a size to pass a drill of maximum dimensions; a drive bushing for said opening; locking members operative between said table and said drive bushing; and means associated with said bushing for disengaging said locking means, said means being actuated by the insertion of lifting means in suitable receptive openings in said bushing.
40. 24. In rotary well drilling equipment, the combination of: a support; a rotary table turnably mounted on said support, said table having a centralized bushing receiving opening therein; a drive bushing for said opening; locking members operative between said table and said drive bushing; and means associated with said bushing for disengaging said locking means, said means being actuated by the insertion of lifting means in suitable receptive openings in said bushing.
45. In testimony whereof, I have hereunto set my hand at Los Angeles, California, this 23rd day of February, 1923.

FREDERIC W. HILD
